ELECTRIC CIRCUIT BREAKER

Hendrik A. Hidde Nijland, Laren, Netherlands

Application October 30, 1937, Serial No. 172,029
In the Netherlands November 17, 1936

3 Claims. (Cl. 200—150)

The invention relates to a circuit-breaker for high voltage such as is used in electric power stations and substations for the distribution of electricity and the protection of the distributing networks, more especially to a circuit-breaker, in which the contact make and break element, comprising fixed contacts and a movable contact-knife cooperating therewith, is mounted in a metal tank filled or adapted to be filled with insulating fluid, for instance mineral oil.

Circuit-breakers, for instance automatic switches, change-over switches, hand switches and the like, which have to switch often and under unfavorable conditions and whose contacts and contact knives are thereby liable to heavy wear and tear, should be adapted to readily be rendered dead in order that they may be inspected and repaired. Up till now such circuit-breakers are therefore connected with the live network (bus bar system, overhead line, cable) through other switches, so called isolating switches. These isolating switches were only used for disconnecting the main circuit-breaker from the network, but only after the main circuit-breaker had opened the circuit, as they are ordinarily not adapted to switch while under load. As viewed from a purely electrical standpoint, such isolating switches do not serve any purpose. They render the switchgear complicated, bulky and expensive.

The invention has for its object to avoid the necessity of using isolating switches, which up till now are indispensable and provides a main circuit-breaker (by which is meant a switch adapted to make and break contact under normal load or under overload), the composite parts of which can be inspected or repaired, without the necessity of disconnecting the switch from the network by means of separate isolating switches.

The invention consists in connecting the fixed contacts of the circuit-breaker to leading-in conductors passed through insulators in the wall of the tank in such a manner that the entire contact make and break element can be removed from the tank and reintroduced, while the leading-in conductors are alive. The leading-in conductors may therefore be connected to the network without interposing isolating switches. A secondary advantage thereof is that no accidents can be caused when the wrong isolating switch is operated, which in practice sometimes occurs. When the main circuit-breaker is to be inspected, the contact make and break element is to be entirely removed from the tank so as to be remote from parts that are live. Switchgear

composed of such circuit-breakers is simple and cheap and, besides, occupies relatively little space.

In accordance with the invention, each of two fixed contacts of the circuit-breaker may be electrically connected and mechanically secured to a contact-socket engaging either a plug provided at that end of the corresponding leading-in conductor, which extends into the tank, or engaging the plug-shaped end of said conductor.

It is especially advantageous for the metal tank to be composed of two vertical tubular casings communicating near their top ends, the leading-in conductors being passed into said casings through or in the vicinity of the bottoms thereof. Since with this construction the leading-in conductors are each provided in an individual casing and in the lower portions of the tank, their ends will remain comparatively far below the lowered liquid level (provided that the tank is filled with an insulating liquid) after the contact make and break element has been removed.

Furthermore, and in accordance with the invention, the fixed contacts may be mounted in the axis of one of the tubular casings and secured to an insulating bush provided within said casing, whereas the contact-knife may be arranged and be movable in the axis of said casing. This offers the advantage that the contact make and break element may have a substantially circular external cross-section throughout, so that the electric field distribution in the circuit-breaker may be substantially radial, whereby a uniform load of the dielectric can easily be obtained. With a view thereto, the tubular casing may surround the contact make and break element with relatively little clearance, so that only a small amount of insulating material is required. As a consequence, the circuit-breaker is relatively cheap to make and is not very dangerous in case of fire, provided that oil is used as an insulating fluid.

Another advantage of said arrangement is that the circuit-breaker can be made so as to allow the contact-knife to be withdrawn lengthwise from the tubular casing or inserted thereinto, while the fixed contacts are alive. This construction permits of ready change of the function of the circuit-breaker. For instance, instead of an automatically or manually movable contact-rod, a thin, conducting wire tightened between two contact rings and adapted to melt when overloaded may be used for bridging the fixed contacts. The circuit-breaker can, in that

case, also serve as a fuse, and be used, for instance, for protecting small transformers. Moreover, the possibility of entirely removing the contact-knife from the tank is of great importance from the standpoint of safety. If it is required to overhaul an apparatus or a cable at the outgoing side of the circuit-breaker, one need only remove the contact-knife (or knives) from the tank to make perfectly sure that the contacts are disconnected from each other.

To illustrate the above, reference is had to the drawings, which by way of example show some embodiments of the invention. In the drawings:

Fig. 1 is a vertical sectional view of a circuit-breaker in accordance with the invention.

Fig. 2 is part of a sectional view corresponding to Fig. 1, during the withdrawal from the tank of the inner parts of the circuit-breaker.

Figs. 3 and 4 are a front elevation and a side elevation respectively, of a triple-pole circuit-breaker connected to a bus bar system and to a cable, and

Figs. 5 and 6 are an elevation and a cross-sectional view respectively, of a melting fuse, drawn to an enlarged scale.

In Fig. 1, the numeral 1 designates a rod-shaped contact-knife adapted to cooperate both with a fixed contact 2 having spring contact fingers 3 and with a fixed contact 4 having spring contact fingers 5, the fingers 3 and 5 being arranged in circular series around the contact-rod 1. The contact-rod 1 is mounted in the axis of a metal tubular casing 6 and is adapted for lengthwise movement and for withdrawal from and reinsertion into the tank of the circuit-breaker by means of a rod 7 arranged in alignment with the contact-rod 1 and connected thereto through an insulator 8. The fixed contact 2 is directly connected, both electrically and mechanically, to a contact-socket 9 having spring contact fingers 10 engaging a plug shaped end 11 of a leading-in conductor 12 which is passed through an insulator in the bottom of the tubular casing 6 and connected with its other end to a distributing bus bar 13. The fixed contact 2 and the contact-socket 9 are mounted on an insulating support 14, secured by means of an insulating and threaded sleeve 15 to an insulating bushing 16 extending through substantially the entire length of the tubular casing 6.

The fixed contact 4 has a screw connection with one end of a sleeve 17 of highly conductive metal fitting into the bushing 16, the other end thereof being connected through a horizontal conductor 18 to the top end of a second conductive sleeve 19. The latter is surrounded by an insulating bushing 20 mounted in a tubular metal casing 21. The conductive sleeve 19 is provided at its lower end with a contact-socket 22 having a circular series of spring contact fingers 23 engaging the plug-shaped end of a leading-in conductor 25, which passes through the bottom of the casing 21, and whose other end extends into a cable junction box 26. The horizontal conductor 18 is surrounded by an insulating bushing 27 and is mounted in a receptacle 28 interconnecting the tubular casings 6 and 21. Provided in this receptacle 28 is a current transformer of the ring type 29 for protective or metering purposes. The current transformer of the ring type in the receptacle may be substituted by a current transformer having a primary coil, or by a relay having a high tension coil.

The metal tank of the circuit-breaker, consisting of the vertical casings 6 and 21 and the

connecting receptacle 28, is closed at the top side by means of a loose insulating plate 30, which itself is covered by a metal plate 31. Said plates are supported by bosses 30a of the wall of receptacle 28. The bush 16, the fixed contacts 2 and 4, the conductive sleeve 17 and the contact-socket 9 are secured to the plates 30, 31, by means of an insulating tube 32, one end of which has a screw connection with the fixed contact 4, the other end passing through the plates 30, 31. The latter end is provided with a screw cap 33. An insulating sleeve 34, which projects into a circular groove 35 of the plate 30, and holds the bushing 16, the sleeve 17, the fixed contacts 2 and 4 and the contact-socket 9 in their proper places, when the screw cap 33 is tightened.

Said cap also serves to guide the rod 7 secured to the contact-rod 1. In a similar manner, the bushing 20, the sleeve 19 and the contact-socket 22 are secured to the plates 30, 31 by means of an insulating tube 36. The lower end of this tube is screwed into the contact-socket 22, whereas the top end passes through the plates 30, 31 and is engaged by a screw cap 37. An insulating sleeve 38 extending into an annular groove 39 of the plate 30 holds the bushing 20, the sleeve 19 and the contact-socket 22 in their proper places. The tank of the circuit-breaker is closed by a cover 40, through which project only the screw cap 33 and the operating rod 7. Mounted on the cover is a box 41 (shown in dash lines) enclosing an operating mechanism.

After removal of the cover, the interior parts of the circuit-breaker, with the exception of the leading-in conductors 12 and 25, can be hoisted from the tank by means of an eye 42 (Fig. 2), without it being necessary first to release any connection. If the tank is filled with an insulating liquid, the level of the liquid will be lowered through a considerable distance owing to the withdrawal of the interior parts (Fig. 2). However, since the leading-in conductors 12 and 25 are mounted in the lower portions of the tubular casings 6 and 21, they will even then remain a sufficient distance below the liquid level. When the interior parts and especially the contact-sockets of the circuit-breaker are to be inspected, it is not necessary for the busbar and the cable to be rendered dead. Consequently, the usual isolating switches at the incoming and the outgoing side of the main circuit-breaker are redundant.

In accordance with Figs. 3 and 4, three circuit-breakers in accordance with the invention are combined to form a triple-pole circuit-breaker. Through a common cable junction box 43, the circuit-breaker is connected to a triple-conductor cable.

The circuit-breaker is mounted on a chamber 44 containing a triple-busbar system 45. Also the cover 40 and the operating mechanism may be common to the three unipolar circuit-breakers.

It is not necessary for each of the contact make and break elements of a multipolar circuit-breaker to be mounted in an individual tank; they may also be accommodated in a common tank. Furthermore, it is obvious that other arrangements may be used. The leading-in conductors 12 and/or 25 could also pass laterally into the tubular casings 6 and 21, respectively. The circuit-breakers may be arranged horizontally. Furthermore, they can be provided in the ordinary manner with a gas vent, an oil level gauge and other auxiliaries. When the contact-rod has been withdrawn from the circuit-breaker, it is

very easy for an earthing apparatus or for a voltage indicator to be inserted. Consequently, it is not necessary to make special provisions for this purpose, as hitherto required.

5 The contact-rod in accordance with Figs. 5 and 6 consists of two parallel rods 46 of insulating material, which on either end carry a common contact ring 47, 48 adapted to engage the contact fingers 3, 5 of the fixed contacts 2, 4 diagrammatically shown in dash lines. The contact rings are interconnected by a thin, conductive wire 49 adapted to melt when carrying an excessive current. If, therefore, the circuit-breaker is provided with such a contact-rod, it can be used as a 10 switchable fuse. Since the contact-rod can be withdrawn while the fixed contacts are under tension, the fuse wire can easily be renewed.

15 The special construction of a circuit-breaker in accordance with the invention enables one and the same bay of a switch-gear embodying the circuit-breaker to be selectively provided either with a hand switch, or with an automatic switch (oil switch), or with a switchable fuse, without it being necessary for said bay, which forms an 20 integral part of the switchgear (reference being had, for instance, to metalclad switchgear) to be modified, or for the bay (or for that portion of the switchgear to which the bay is allocated) to be 25 rendered dead.

30 The invention, therefore, provides a universal circuit-breaker. Since the electric field distribution in a circuit-breaker in accordance with the invention, can be very favourable, it is not necessary for a circuit-breaker for very high tension, say 150 K. V., to differ, or to materially differ 35 from a circuit-breaker for less high tension, say 10 K. V.

What I claim is:

1. A circuit breaker for high voltage currents, 40 comprising a fixed metal tank comprising two vertical tubular casings communicating with one another at their top ends and adapted to be filled with an insulating fluid such as mineral oil, insulators mounted adjacent the bottoms of said casings in the wall thereof, fixed leading-in conductors passed through said insulators and extending with one of their ends into said casings, a contact make and break element comprising fixed switch contacts and an axially movable plugging contact cooperating therewith and arranged in one of the tubular casings with the axis of the movable plugging contact in the axis of that casing, contact means connected both electrically conductively and mechanically rigidly to said fixed switch contacts, contact means provided at said ends of the leading-in conductors, the contact means connected to the fixed switch contacts and those provided at the leading-in conductors releasably engaging one another so as to permit the contact make and break element to be 45 as to permit the contact make and break element

to be entirely withdrawn from and inserted into said tank, while the leading-in conductors are alive and the tank with the leading-in conductors remains in place.

2. A circuit breaker for high voltage currents, 5 comprising a fixed metal tank adapted to be filled with an insulating fluid such as mineral oil, insulators positioned in the wall of said tank, fixed leading-in conductors passed through said insulators and extending with one of their ends into said tank, a contact make and break element comprising fixed switch contacts and an axially movable plugging contact cooperating therewith, an insulating bushing in which the contact make and break element is coaxially arranged and which keeps the fixed switch contacts of said element spaced apart, contact means connected both electrically conductively and mechanically rigidly to said fixed switch contacts, contact means provided at said ends of the leading-in conductors, the contact means connected to the fixed switch contacts and those provided at the leading-in conductors releasably engaging one another so as to permit the contact make and break element to be entirely withdrawn from and inserted into the tank, while the leading-in conductors are alive and the tank with the leading-in conductors remains in place.

3. A circuit breaker for high voltage currents, 30 comprising a fixed metal tank comprising two vertical tubular casings communicating with one another at their top ends and adapted to be filled with an insulating fluid such as mineral oil, insulators mounted adjacent the bottoms of said casings in the wall thereof, fixed leading-in conductors passed through said insulators and extending with one of their ends into said casings, a contact make and break element comprising fixed switch contacts and an axially movable plugging contact cooperating therewith and arranged in 40 one of the tubular casings with the axis of the movable plugging contact in the axis of that casing, resilient contact sleeves of which the one is directly connected to one of the fixed switch contacts and is arranged in the casing with the contact make and break element and the other is arranged in the other casing and is connected to the other fixed switch contact through a bridging conductor, plugs provided at said ends of the leading-in conductors, the resilient contact 45 sleeves connected to the fixed switch contacts and the plugs provided at the leading-in conductors releasably engaging one another so as to permit the contact make and break element to be entirely withdrawn from and inserted into the tank, while the leading-in conductors are alive and the tank with the leading-in conductors remains in place.

HENDRIK A. HIDDE NIJLAND.
